UNITED STATES PATENT OFFICE.

ALVIN D. KEENE, OF WEST MANSFIELD, OHIO, ASSIGNOR TO WESTINGHOUSE ELECTRIC & MANUFACTURING COMPANY, A CORPORATION OF PENNSYLVANIA.

ELECTRIC FURNACE.

Application filed September 24, 1926. Serial No. 137,481.

My invention relates to electric furnaces and particularly to furnaces of the resistor type.

- An object of my invention is to provide 5 a resistor-supporting-and-protective means to which resistor members may be secured to constitute an assembled unit before placing the same in position in an electric furnace.
- 10 Another object of my invention is to provide a plurality of resistor-supporting-and-protective frames which shall simplify the assembly of electric heating units in an electric furnace.
- 15 Another object of my invention is to provide resistor-supporting-and-protective means for electric resistor members that shall be removable from an electric-furnace chamber.

- 20 Another object of my invention is to provide a unitary roof structure for an electric furnace that shall facilitate the positioning of heating units in the heating chamber and the inspection of the refractory 25 brick work in the furnace walls.

In practicing my invention, I provide a substantially rectangular metallic casing having an open top and a door opening in one of the end walls thereof. The bottom and walls 30 of the casing are lined with suitable refractory heat-insulating bricks. A plurality of metallic frames, on which electric resistors are adapted to be secured, are positioned along the bottom and the side walls 35 of the furnace chamber. The bottom metallic-resistor-supporting frame serves to maintain the frames extending along the walls of the chamber in position. Another metallic cast frame is positioned on the top of the 40 side frames to prevent the same from tipping inwardly at the top. Each of the cast metallic frames is adapted to support resistor heating units on the sides thereof adjacent to the walls of the furnace chamber. The 45 metallic frames, when assembled within the chamber, form a suitable work-receiving chamber.

A unitary roof structure comprises a metallic frame work which supports an arch-bound, heat-insulating brick work that may be removable from the walls of the furnace chamber in a vertical direction and is so arranged that the metallic frame work may be secured to the metallic casing when in 55 operative position. A vertically movable

door member is provided for so closing the opening in one of the end walls of the furnace structure that substantially no air is permitted to leak into or out of the furnace chamber during operation of the furnace. 60

In the accompanying drawings:

Fig. 1 is a view, in longitudinal vertical section, of the furnace structure embodying my invention;

Fig. 2 is a front view, in partial vertical section, of the furnace structure illustrated in Fig. 1;

Fig. 3 is a side view, partially in section, of a resistor-supporting-and-protecting means employed in the furnace chamber 70 illustrated in Figs. 1 and 2;

Fig. 4 is a partial front elevational view of a resistor-supporting-and-protecting means disposed along the side walls of the furnace structure illustrated in Figs. 1 and 2, 75

Fig. 5 is a sectional view of the device illustrated in Fig. 4, taken along the lines V—V; and

Fig. 6 is a view, partially in section, of a resistor-supporting-and-protective means 80 disposed along the bottom wall of the furnace structure illustrated in Figs. 1 and 2.

In the drawings, a furnace structure 11 comprises a metallic casing 12, a roof structure 13, heating units 14, 15 and 16 and a 85 vertically movable door 17.

The metallic casing 12 comprises an end wall 18, a bottom 19, a pair of side walls 21 and a plurality of front castings 22 and 23. The castings 22 and 23 are secured together by suitable latterly extending flanges 24 (only one of which is shown) through which a clamping bolt 25 may extend. The bottom 19 is secured to the end and side walls of the casing 12 by angle irons 26 90 which extend around the periphery of the bottom portion of the casing 12 and are secured thereto by suitable rivets 27.

A plurality of angle-irons 28 extend across the bottom 19 and are secured thereto 100 by suitable means, such as rivets 29. The angle-irons 28 serve to strengthen the bottom 19 and to lend rigidity thereto.

The castings 22 and 23 are provided with inwardly extending flanges indicated by the broken lines 31 and 32, see Fig. 2, which register with the side walls 21 of the casing 12. The inwardly extending flanges are secured to the side walls 21 by rivets 33.

A plurality of angle-irons 34 extend along 110

the upper edge of the casing side and end walls and are secured thereto by rivets 35. It is to be understood that I may weld the various members together to replace the rivets illustrated in the drawings, if I so desire.

The front casting 22 comprises a vertically extending portion 36 and a horizontally extending shelf 37 having a recessed portion 38. The shelf 37 is supported by a pair of brackets 39 (only one of which is shown). Suitable refractory material 41 is disposed in the recessed portion 38.

The casing 12 is lined with heat-insulating brick 42, defining a furnace chamber 43.

A resistor-supporting-and-protective frame 44 of the heating unit 16 is disposed along the bottom wall 45 of the furnace chamber 43, and a pair of resistor-supporting-and-protective frames 46 (see Figs. 1 and 2) of the heating units 15 are disposed along the longitudinally extending walls 47.

A resistor-supporting-and-protective frame 48 of the heating unit 14 is supported by the frames 46 and is interlocked therewith to prevent the frames 46 from falling inwardly into the furnace chamber 43. The assembly arrangement of the supporting frames 44, 46 and 48 is such that a working chamber 49 is formed within the chamber 43.

Resistors 50 are securely clamped between refractory electrically-insulating blocks 51 which are secured to the frames 44, 46 and 48, respectively, by clamping plates 53 and bolts 54.

The bottom resistor-supporting-and-protective frame 44 comprises a casting having a solid bottom 55, upwardly extending side portion 56, horizontally extending flanges 57 and 58, and a plurality of downwardly extending lugs 59. The lugs 59 are tapped and screw threaded at 61 to receive bolts 54 to secure the clamping plate 53 and the insulating blocks 51 to the supporting frame 44.

The frames 46 are disposed along the side portions 56 of the frame 44 and are thereby prevented from sliding inwardly into the furnace chamber 43. The resistor-supporting-and-protective frames 46 are so cast that a plurality of openings 62 and 63 are provided, thereby reducing the weight of the frame member but, at the same time, providing protective and supporting means for resistors secured thereto. The frames 46 have grooves 64 therein and lugs 65 thereon which are provided with tapped holes 66. The resistor insulating blocks 51 are disposed in the grooves 64 between the lugs 65 and secured thereto by the clamping plate 53 and the bolts 54, as has been previously mentioned.

The castings 46 are provided also with a horizontally extending rim 67 which extends substantially along the periphery thereof

and with an upwardly extending flange 68 which also extends substantially around its periphery.

The top casting 48 is similar to the side castings 46 and is provided with a downwardly extending rim 69 which rests on the laterally extending flange 67 of the casting 46. The flange 67 extends inwardly into the furnace chamber 43 substantially as illustrated in Fig. 2 of the drawings. It is, therefore, evident that the castings 46 are prevented from falling inwardly into the furnace chamber 43. The supporting frame 48 is provided with lugs 65 and grooves 64, substantially as illustrated in Fig. 4 of the drawings, which serve to maintain the insulating blocks 51 in position.

The bottom portion 55 of the resistor-supporting member 44 serves as a supporting floor for material to be heated in the furnace chamber 49 and a muffle for the radiant heat rays emitted from the electric resistors 50.

As illustrated in Fig. 1 of the drawings, the resistors 50 may extend downwardly through the refractory brick work 42 and be secured to a suitable terminal block 69 so that the resistors 50 may be connected to an electric circuit by a conductor 71. The resistors supported by the top and side castings 48 and 46 may be brought out through the side walls in a suitable manner and be connected to an electric circuit.

The roof structure 13 comprises a pair of longitudinally extending channel members 72, a transversely extending channel member 73 and a front casting 74. The channel members 72, 73 and the casting 74 are suitably secured at their respective ends by rivets 75. The longitudinally extending channel members 72 are provided with angle irons 76 secured to the inner lower edge thereof by rivets 75 and serve to support an arch bound brick-work 78. The brick work 78 is covered with a suitable sheet of metal 81 that is secured to the channel members 72, 73 and the casting 74.

A plurality of eye bolts 84 are secured to the channel members 72 whereby the roof structure 13 may be lifted free of the furnace structure. The front casting 74 is provided with a horizontally extending upturned portion 85 which may be partially filled with a pulverulent material. Suitable guides 87 are secured to the castings 74 and 23 and serve to maintain the door 17 in operative relation to the furnace structure.

The door 17 comprises a pair of castings 88 and 89 which are suitably secured together by bolts 90. The casting 88 is provided with inwardly extending bottom and side flanges 91 and 92 which serve as a support for the brick work 93. The upper casting 89 is provided with an inwardly extending flange 94 having a depending curved por-

tion 95 and an upwardly extending lug 96 to which a chain 97 is secured. A depending flange 98 serves to prevent the brick work 93 from falling inwardly into the furnace 5 chamber. The curved portion 95 registers with the portion 85 and the pulverulent material 86 therein to thereby provide a sealed joint between the door on the furnace wall.

A lifting mechanism 100 for the door 17 10 comprises a pivotally mounted lever 101 that is supported by a bracket 102. The lever 101 is secured to the bracket 102 by a suitable pin 103 and has a segment 104 and a counter-balancing weight 105 secured to the respective 15 ends thereof. The chain 97 is secured to the segment 104 in any suitable manner. By pulling downwardly upon the counter-balancing weight 105, the door 17 may be lifted vertically.

20 The resistor - supporting - and - protective frames 44, 46 and 48 are preferably made of metal, such as nickel steel, that is resistant to oxidation when subjected to high temperatures. By making the side frames 46 and the 25 top frame 48 of a casting having a plurality of openings 62 and 63 therein, the amount of necessary material is reduced but protective and supporting means for the resistors is still provided. Since the bottom frame 44 30 must support material to be heat treated, I make the bottom portion 55 thereof solid to prevent the material being heated from coming into contact with the resistor 50 disposed thereunder.

35 By removing the roof structure 13, the brick work at the sides and the bottom of the furnace chamber 43 may be inspected, and the resistor supporting and protective frames 44, 46 and 48 may be inserted therein or re- 40 moved therefrom as a unit.

My invention provides an electric furnace in which the resistor units comprise a plurality of removable cast frames, preferably of nickel steel, that may be placed within the 45 furnace chamber as an assembled unit. I provide also a removable unitary roof structure that may be lifted free of the side walls of the furnace chamber, whereby the refractory heat-insulating material and the 50 heating units may be inspected with ease.

Various modifications may be made in the device embodying my invention without departing from the spirit and scope thereof. I desire, therefore, that only such limitations shall be placed thereon as are imposed by 55 the prior art and the appended claims.

I claim as my invention:

1. A supporting and protective means for electric resistor heating units comprising a plurality of upwardly extending cast metallic frames having a plurality of openings therein and a cast metallic frame supported by said upwardly extending frames and interfitting therewith. 60

2. A supporting and protective means for electric resistor heating units comprising a plurality of upwardly extending cast metallic frames having a plurality of openings therein, a cast metallic frame supported by said upwardly extending frames and interfitting therewith, said frames being provided with grooves for receiving refractory electric-insulating resistor clamping members and means for positively securing them thereto. 70

3. A supporting and protective means for electric resistor heating units comprising a cast metallic frame, said frame having recesses therein for receiving refractory electric insulators adapted to receive an electric resistor member, and clamping means for securing said insulators to the frame. 80

4. A supporting and protective means for electric resistor heating units comprising a plurality of upwardly extending frame members having a plurality of openings therein, a cast metallic frame member disposed at the top of said upwardly extending frame members in interfitting relation therewith, and a cast metallic frame member disposed at the 85 bottom of said first named frame members in interfitting relation therewith, each of the frame members being provided with grooves for receiving resistor supporting and insulating members and means for clamping said 90 members to the frame members. 95

In testimony whereof, I have hereunto subscribed my name this 20th day of September, 1926.

ALVIN D. KEENE.
